UNITED STATES PATENT OFFICE.

ALFRED N. WARREN, OF TOLEDO, OHIO.

CARTON SPICE-CABINET.

SPECIFICATION forming part of Letters Patent No. 691,990, dated January 28, 1902.

Application filed January 3, 1901. Serial No. 42,002. (No model.)

To all whom it may concern:

Be it known that I, ALFRED N. WARREN, a citizen of the United States, residing at Toledo, in the county of Lucas and State of Ohio, have invented certain new and useful Improvements in Carton Spice-Cabinets; and I do hereby declare the following to be a full, clear, and exact description of the invention, such as will enable others skilled in the art to

which it appertains to make and use the same.

My invention relates to improvements in cabinets for containing and delivering cartons of spices, pepper, and the like of different sizes and provided with means for retaining the cartons in different compartments and withdrawing one carton at a time from a compartment, the cabinet to be placed in a suitable place in a store and employed as a convenient means of keeping and handling the goods and also serving as an advertising means for the manufacturer of the goods.

The invention consists in certain novel constructions, combinations, and arrangements of parts, as will be hereinafter described and claimed.

In the accompanying drawings, Figure 1 is a perspective view of a cabinet constructed in accordance with my invention. Fig. 2 is a vertical section taken through one of the compartments and showing the construction and arrangement of the operating mechanism.

1 in the drawings represents the casing of the cabinet, which is provided with a series of vertically-arranged compartments 2, a horizontal base 3, which is preferably extended to form a shelf 4, a series of rearwardly-projecting extensions or housings 5 for the accommodation of the ejectors 6 when the latter are in a retracted or withdrawn condition, and a series of apertures or openings 7 at the lower ends of the compartments 2 for the withdrawal of the cartons from the respective compartments.

The cabinet may be of any suitable dimensions, two or two and a half feet high by four feet long, and may be constructed of any suitable material, but preferably light wood and provided with any suitable number of compartments, and all the compartments may be of the same dimensions; but the apertures 7 at the lower ends of the same are preferably varied, so as to admit of different-sized car-

tons—as, for instance, one-ounce packages or two-ounce packages—being withdrawn from the respective compartments. The cabinet 5 is also provided with a hinged cover 8, and the rear compartments 5 are also preferably provided with hinged covers 9. The hinged cover 8 prevents the dust from getting into the cabinet and admits of the insertion of new packages into the cabinet. The hinged covers 9 facilitate the insertion and removal of the ejector 6 into position within the cabinet and its removal for repairs. The front of the case may be provided with glass, if desired, to exclude dust, the lower front ends of the compartments of course being left open for the forcing out of the packages by the ejectors 6 onto the shelf 4.

For holding the packages 10 within the compartment and yet admit of their being seen from the outside and to disclose how many packages are still in each compartment each wall 11 of the cabinet has attached to its front edge a vertically-arranged strip 12, extending on opposite sides of each wall or partition 11, with the exception of the end walls or partitions, in which case the strip extends only in one direction.

The ejector 6 is made of slightly less height 80 than the height of a package to be removed, so that only one package will be engaged at a time and the ejector will be free to be moved back and forth. A recess 14 is provided in the rear of the ejector, in which recess the 85 spring 13 is located and connected by one of its ends to said ejector, while its other end is connected to the wall 16 of the cabinet, which is the rear vertical wall of the compartment 17. By this construction and arrangement 90 the spring can be accommodated within the aperture 14 when the ejector 6 is in its re-turned condition and will also serve to hold the ejector in said condition until it is drawn forward by the operating-rod 18, connected 95 to said ejector, and automatically return the ejector into the chamber or compartment 17 as soon as the hand of the operator is removed from the rod 18. The bottom or floor 3 of the cabinet is provided with a series of 100 longitudinally-extending slots 15. Within each slot an upturned projection of an operating-rod 18 works, the said upturned projection being attached to the under side of

the ejector 6, the rods being held in position and guided in their movements by passing through apertures provided in the cabinet, as clearly shown in the drawings. The provision of the shelf 4 forms a receptacle for retaining a package or packages as they are withdrawn from the cabinet, and thus avoids any liability of the packages accidentally falling on the floor or requiring the operator to immediately withdraw a package as soon as it is ejected from the cabinet. It will also be observed that with my construction and arrangement the ejectors are never drawn outside of the cabinet when being operated, but are always contained within the cabinet, and it will further be observed that the ejectors are made of such a size and so located as to always push out a single package at a time and that as the ejectors are automatically returned to the compartments 17 other packages are automatically lowered to positions in front of the ejectors.

Having thus described the invention, what is claimed as new, and desired to be secured by Letters Patent, is—

25 A cabinet for containing and delivering car-

tons, comprising a vertical housing and a rearwardly-projecting horizontal housing, said housings having compartments formed in them which are open at the top, hinged covers 30 for closing both of the said housings, the compartments of the horizontal housing opening into the lower ends of the compartments in the vertical housing, and the vertical housings having outlet-openings at their lower 35 ends, a series of ejectors arranged in the compartments of the horizontal housing, a rod for pulling each ejector forwardly into the lower end of the vertical compartments, and springs connecting the ejectors with the 40 rear wall of the horizontal housing for automatically returning the ejectors in the said housing after a carton has been forced out of one of the vertical compartments, substantially as described.

45 In testimony whereof I hereunto affix my signature in presence of two witnesses.

ALFRED N. WARREN.
